CLOTH WINDING RACK

Charles D. Gaudreau, Springfield, Mass., assignor
to Bay State Tool & Machine Co., a corporation
of Massachusetts

Application July 10, 1933, Serial No. 679,701

4 Claims. (Cl. 206—51)

This invention relates to cloth-winding racks.

An object of my invention is to provide a cloth-winding rack structure, which is extremely rigid in its construction. It is used for the usual and well known method of winding cloth that is provided with a nap, or pile.

The purpose of this rack is to prevent the crushing of the nap, or pile, of the fabric from the time the cloth is finished at the factory, or mill, until it is sold to the customer. When the roll of cloth is complete, the different turns, or layers, will not come into contact, or engage each other and, therefore, will not crush, or destroy, the pile, or nap, of the fabric. All pressure between the layers is, therefore, removed, since the weight of the cloth is supported at its edge only by means of the hooks on the rack, or frame, thus spacing the layers, or turns, from each other, so that the nap, or pile, will not be crushed. This is necessary in such fabrics as chiffon, silks, velvets, imitation furs, rayon, and all fabrics that are formed, or provided, with a raised pile, or nap, surface that would be injured by having the layers, or turns, of the cloth come into contact with each other, whereby the nap, or pile, will be crushed.

The invention comprises two triangular-shaped frame members, each of which is provided with a plurality of cloth-attaching hooks that are spaced from each other. These hooks are located on diagonally arranged arms of the triangular-shaped frame members and point outward from the center portion. These two said frames are connected together by a suitable bar, usually of wood, thus completing the structure for winding cloth thereon.

The principal object of my present invention is to materially strengthen these triangular-shaped frames, so that when the cloth is attached by its selvaged edge, at, or near, the outer ends of the arms, the frames will not buckle, or bend inward, which is now a common defect. In the event that the frames do bend, or buckle inward, the different layers, or turns of cloth, often become detached from the hooks, thus ruining the sale of the cloth, by reason of the nap, or pile, becoming crushed, or spoiled.

My improvement particularly relates to the means for connecting together the adjacent, inner ends of the diagonally arranged bars of the triangular-shaped frames. This connecting means comprises a plate member, the center portion of which is materially wider than the width of the diagonally arranged bars to which it is attached, thereby providing additional strength to which

the connecting bar, or shaft, is attached for connecting the two end frames together.

This wide plate member is formed with openings for firmly attaching the longitudinal bar that connects the frame together, so as to prevent any inward movement of the end frames.

Referring to the drawing:—

Fig. 1 is an elevational view, partly in section,— illustrating the two end frames that are connected together with the longitudinal bar, showing the different layers of cloth attached thereto.

Fig. 2 is an end view of Fig. 1, looking from the left, on the line 2—2, showing the two triangular-shaped frames.

Fig. 3 is a transverse, sectional view, on the line 3—3 of Fig. 1, illustrating the longitudinal connecting bar, in section, and the successive turns of the cloth on the hooks of the end frames, or racks.

Fig. 4 is a perspective view of one of the end frames, disconnected from its connecting bar.

Fig. 5 is a detail view of one of the cloth-attaching plates, formed with the hooks, on which the selvage edge of the cloth is connected, and

Fig. 6 is a perspective view of one of the connecting plate members, for securing together the adjacent, inner ends of two of the diagonal bars of the end frames and to which the longitudinal connecting bar is connected.

Referring to the drawing in detail:—

1 designates, as a whole, the two end frames, or rack members, each of which is formed with the two triangular-shaped strips, comprising the portions 2, 3, and 4, and 5, 6 and 7.

The portions 2 and 5 are arranged parallel to each other and the members 3 and 4 are arranged at an angle to the portion 2 that extends diagonally inward toward the center. The oppositely located members, 6 and 7, are also arranged at an angle to the portion 5 and extend diagonally inward, as shown. The adjacent, inner ends of the members 3 and 6, and 4 and 7, are connected together, by means of the rigid plate member, indicated as a whole at 8, in Figs. 4 and 6, which comprises the wide, center portion 9, with the two integral bent arms, or extensions, 10 and 11, which are formed with the openings 12 and 13, for receiving the rivets 14, that are passed through openings in the arms 3 and 6, and 4 and 7, as clearly shown in Figs. 2 and 4. Particular attention is directed to the fact that the center portion 9 and extensions 10' and 11' are materially wider than the two bent, integral arms 10 and 11, which are of the same width as the members 3, 6, 4 and 7.

Great rigidity and strength is provided at the

bends 9', since the extension portions 10' and 11' are of the same width, as the center portion 9. The arm members 3, 6, 4, and 7 extend, as shown, to the bends 9', whereby, the full strength of the 5 width 9 of the plate is obtained, because this full width is provided at 10' and 11' of the plate 8. This is a very important feature and produces a strong end frame and one that will not bend at any time, when in use. The width of the arms, 10 as shown at 10 and 11, is the same as the portions 3, 6, 4, and 7. 15 designates the bar of wood which connects the two end frames 1-1 together, as shown in Fig. 1. This bar is firmly secured to the broad surface 9 of the connecting 15 plates 8, by passing the bolts 16 through the square openings 17. By means of this construction, the end frames 1 are prevented from buckling, or bending inward, when the different turns of cloth, indicated in Fig. 3, at 18, are connected to the hooks 19, of the plates 20, beginning with the innermost hook, as shown in Fig. 3. These plates are riveted to the arms 3, 4, 6, and 7. By reason of the portions 2, 3, and 4 of one 20 triangular-shaped frame and portions 5, 6, and 7, being a continuous piece and integral with the members 2 and 5, there is no possibility of these arms bending, when in use. The added, or wide surface portion 9, of the rigid connecting plate 8, provides a large, broad bearing surface for the 30 ends of the longitudinal, wooden, connecting bar 15, which prevents the end frames 1 from tipping inward, when in use.

The rack is used as follows:—Usually, two operatives, one standing at each end of the completed structure, attaches the inner end of the cloth, indicated at 21, to the first, or innermost, hook 19. This inner layer is indicated in Fig. 1, at 22. The operatives then rotate the frame through a quarter turn, bringing the next pair 40 of hooks into use, and connecting the selvage edge of the cloth thereto. This operation is repeated, until the entire racks, or frames, are filled, as shown in Figs. 1 and 3.

From this description, it will be seen—that I 45 have provided a very rigid, cloth-winding rack that will not bend, or buckle, when in use, thus preventing the cloth from becoming detached, or sagging on the rack, and the rounded corners 50 23 will not scratch, or deface, a polished counter on which the frames are used; that the two— connecting center plates 8, having the wide, center portion 9, rigidly secure—the arms 3 and 4 and

6 and 7 firmly together, by reason of this substantially wide, strong, center portion 9.

What I claim is:—

1. In a cloth-winding rack, the combination with a pair of substantially triangular-shaped one-piece members, the inner extending arms of each of these members being connected together, the connecting means comprising plates, the center portion of which is substantially wider than its opposite ends, said opposite ends being connected to the inwardly extending arms of the triangular-shaped members. 80 85

2. A cloth-winding rack member for the purpose described, comprising two triangular-shaped members each one of which is formed as an integral one piece, hook members secured to two of the arms of the triangular-shaped member, means for securing together the inwardly extending arm or limb portions of the triangular-shaped members, said means comprising a plate the center portion of which is substantially wider than the end portions which are reduced in width and are equal in width to the limb portions of the triangular-shaped members, and means for attaching the said plates to the triangular-shaped members. 90 95 100

3. A cloth rack comprising, in combination, a pair of one-piece triangular-shaped members having normally spaced ends, bent plate means with reduced extensions for securing the spaced 105 ends of each member together, a bar secured to the plate means of each of said members for securing together the pair of triangular-shaped one-piece members, and hook members on the limbs of each of the triangular-shaped members, 110 as described.

4. A cloth-winding rack, comprising two end members each of which is formed with two one-piece triangular-shaped members, the inner ends of each of the members being separated from each 115 other and connected together with a substantially wide plate at its middle or center portion and having reduced or narrow projections on its opposite ends that are arranged at an angle corresponding with the two limbs of the triangular-shaped members for connecting the apex portion of the triangle together, hook means on the triangular-shaped members for attaching cloth thereto, and a bar for connecting the said plates together. 123
